UNITED STATES PATENT OFFICE

97,227

DESIGN FOR A TEXTILE FABRIC

Curt Erwin Forstmann, Montclair, N. J.

Application January 2, 1935, Serial No. 54,687

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The area included within the broken lines represents the design unit repeated twice.

The design pattern is constituted by the contrasting appearance with a background of rel-

atively long parallel stitches of equal length arranged in groups of different lengths in repeated series, in parallel warpwise rows, the stitches being transverse to the direction of the rows and the groups in adjacent rows being so displaced as to define on the background groups of three irregular ovals *a* arranged herringbone-wise, as indicated by the diagrammatical parallelograms *b*, the ovals being crossed by parallel corrugations, extending in the same direction across the ovals on both sides of the herringbone.

I claim:

The ornamental design for textile fabric as shown and described.

CURT ERWIN FORSTMANN.
